UNITED STATES PATENT OFFICE.

JOE HORN, OF EUREKA, UTAH.

RIFFLE BOARD.

1,419,052.

Specification of Letters Patent. Patented June 6, 1922.

Application filed September 23, 1920. Serial No. 412,152.

To all whom it may concern:

Be it known that I, JOE HORN, a citizen of the United States, residing at Eureka, in the county of Juab and State of Utah, have 5 invented new and useful Improvements in Riffle Boards, of which the following is a specification.

This invention relates to riffle boards for ore concentrating tables, and has for its object 10 the provision of novel means for mounting the riffles of such a board with relation to a wooden base provided for the same.

The invention will be readily understood from the following description of the accompanying 15 drawings, in which—

Figure 1 is a perspective view of a riffle board constructed in accordance with the invention.

Fig. 2 is a transverse section on the line 20 2—2 of Fig. 1.

Fig. 3 is an enlarged fragmentary transverse section.

Fig. 4 is a fragmentary perspective detail of the board.

Fig. 5 is a perspective view of one of the 25 tightening clips.

In the drawings the deck of the concentrating table is shown as formed of the board 1. A layer of tar paper 2 is placed 30 upon the upper face of the board 1 and then wooden spacer strips 3 and riffles 4 are alternately laid upon the tar paper covering of board 1. The strips 3 are, preferably, about an inch wide and three-eighths of an inch 35 thick. The riffles 4 may be either of metal or hard rubber, the latter being preferred in certain classes of work where the acid of the pulp treated upon the concentrating table tends to destroy metallic riffles. The 40 riffles are held in upright position by means of the spacer strips at the opposite sides thereof, said strips being nailed through the tar paper covering to the board 1 by nails 5, preferably, placed along the strips approximately every six inches.

If from warpage or any other cause the

riffles should become loose between the spacer strips, they may be tightened by the use of suitable clips 6. These clips are, preferably, of metal and about three-eighths of an inch 50 square and are adapted to be driven into any space formed between a riffle and a spacer strip for firmly wedging the riffle in position.

A riffle board as thus constructed is 55 cheaply and easily made and readily assembled, the wooden surface presented by the spacer strips having been found by actual test to form as efficient a base as a base of linoleum or the like, and the riffles being 60 held in position by means of the spacer strips in conjunction with the tightening clips 6 forming a rigid construction wherein the riffles are not liable to come loose when subject to ordinary use.

Various changes may be made without departing from the spirit of the invention as claimed.

What is claimed is:

1. A riffle board comprising a wooden 70 deck, a tar paper covering upon said deck, riffle plates upon said covering spaced apart and retained in position by means of spacer strips extending the length of said riffle plate to form a base, said spacer strips being 75 nailed through the tar paper covering to the wooden deck, and tightening clips inserted between said riffle plates and said spacer strips.

2. A riffle board comprising a deck, a section of relatively thin waterproof material covering said deck, riffle plates positioned upon said covering, spacer strips arranged on said covering between the lower portions of said riffle plates, fastening means passing 80 through said spacer strips and said covering, and tightening means positioned between said riffle plates and said spacer strips.

In testimony whereof I have signed my 90 name to this specification.

JOE HORN.
